(57) CLAIM

I claim the ornamental design for a shoe outsole, as shown and described.

DESCRIPTION

FIG. 1 is a bottom view of the shoe outsole;

FIG. 2 is a left side view of the shoe outsole;

FIG. 3 is a right side view of the shoe outsole;

FIG. 4 is a front view of the shoe outsole; and,

FIG. 5 is a rear view of the shoe outsole.

The broken lines showing the boot upper and the remainder of the shoe sole illustrate the portions of the design that form no part of the claim.
